UNITED STATES PATENT OFFICE.

HUBERT R. HUMPHREY, OF KALAMAZOO, MICHIGAN.

GAS-BURNER.

1,396,211.

Specification of Letters Patent.

Patented Nov. 8, 1921.

Application filed August 3, 1920. Serial No. 400,948.

To all whom it may concern:

Be it known that I, HUBERT R. HUMPHREY, a citizen of the United States, residing at Kalamazoo, county of Kalamazoo, 5 State of Michigan, have invented certain new and useful Improvements in Gas-Burners, of which the following is a specification.

This invention relates to improvements 10 in gas burners.

My improvements are particularly designed by me for embodiment in burners for gas stoves of the type shown in Letters Patent to Alfred H. Humphrey, No. 1,245,347, 15 dated November 6, 1917, and I have illustrated my improvements as I have embodied them in such burners although they are readily adapted and desirable for use in other relations.

20 The main objects of this invention are:

First, to provide an improved multiple gas burner in which the gas may be admitted to all or to part of the burner members as desired.

25 Second, to provide an improved gas burner having these advantages which is very simple in structure and simple to manipulate to secure the desired result.

30 Further objects, and objects relating to structural details will definitely appear from the detailed description to follow.

I accomplish the objects of my invention by the devices and means described in the following specification. The invention is 35 clearly defined and pointed out in the claims.

A structure which is a preferred embodiment of my invention is clearly illustrated in the accompanying drawing forming a part 40 of this specification, in which:

Figure I is a detail front elevation of a structure embodying the features of my invention.

Fig. II is an inverted view of the upper member of the burner manifold.

45 Fig. III is an inverted view of the lower member of the burner manifold with the valve mounted thereon, the gas supply pipe being broken away.

Fig. IV is an enlarged detail view mainly 50 in vertical section on a line corresponding to line 4—4 of Figs. II, III, V and VI, with the valve in its closed position.

Fig. V is a detail section through the valve on a line corresponding to line 5—5 55 of Figs. III and IV.

Fig. VI is a detail section through the valve on a line corresponding to line 6—6 of Figs. III and IV.

Fig. VII is an inverted view of the upper member of a manifold of a modified form. 60

In the drawing similar reference characters refer to similar parts throughout the several views, and the sectional views are taken looking in the direction of the little arrows at the ends of the section lines. 65

Referring to the drawing, 1 represents a gas stove of the heater type, 2 a series of tubular foraminated radiating elements disposed in front of the back wall 3. I provide a burner consisting of a plurality of 70 independent burner tubes 4 having tips 5 delivering to the radiating elements 2. The gas delivery nozzles 6 are mounted upon the gas manifold 7 to deliver to the lower ends of these tubes 4, this arrangement being in 75 general that shown in the said patent.

The manifold 7 comprises an upper member 8 having a partition 9 therein dividing it into two chambers as 10 and 11. A bottom plate 12 secured to the member 8 completes 80 these chambers.

The partition 9 in the structure illustrated in Fig. II is a zig-zag partition disposed so that alternate nozzles communicate with each chamber as clearly shown in Fig. II. 85 The gas supply pipe 13 is connected to these chambers through a valve consisting of the casing 14 having ports 15 and 16 therein registering with the ports 17 and 18, respectively, in the bottom member 12 of the manifold, the port 17 opening into the manifold chamber 10 while the port 18 opens into the manifold chamber 11. 90

The valve 19 is rotatable in the casing and is provided with a longitudinal bore or 95 passage 20 communicating with the supply pipe 13. The valve has ports 21 and 22 adapted to be brought into register with the ports 15 and 16, respectively, of the valve casing. The port 21 is elongated or 100 shaped so that it is fully opened prior to the opening of the port 22, both ports being opened by the turning of the valve stem 23 to the left or counter-clock-wise so that the valve may be fully opened thereby delivering 105 gas to all of the burners.

A fixed stop 24 is provided to coact with stops 25 and 26 on the valve stem 23, the stop 25 being in engagement with the stop 24 when the valve is opened and the stop 26 110

being in engagement with the stop 24 when the valve is opened.

This arrangement permits the delivery of gas to half of the burners to their full capacity or to all of the burners to their full capacity or a limited supply of gas to one set of burners with full supply to the other or the admission of a limited supply of gas to one set or group only.

- 10 In the modification shown in Fig. VII, the partition 27 is arranged so that the burner chamber 28 embraces the inner group of burners while the burner chamber 29 embraces or supplies gas to the outer burners.
- 15 Other modifications and adaptations will no doubt be apparent to those skilled in the art to which my invention relates.

My improvements are particularly desirable for embodiment in gas heaters of the type illustrated as they enable the effective operation of the same as conditions may require with a minimum consumption of gas for the heat desired. My improvements are, however, capable of and desirable for embodiment in certain other types of heaters, but I have not attempted to illustrate or describe the same as I believe the disclosure made will enable those skilled in the art to which my invention relates to embody or adapt the same as may be desired.

Having thus described my invention, what I claim as new and desire to secure by Letters Patent is:

1. The combination of a multiple burner comprising independent burner tubes and burner tips, a gas delivery manifold having nozzles delivering to said burner tubes, said manifold being provided with a longitudinally disposed zig-zag partition dividing it into chambers with alternate nozzles opening into each, a gas supply valve comprising a casing having separate ports opening into said manifold chambers and a gas supply connection at one end, and a rotary valve having a longitudinal passage communicating with said supply connection and ports adapted to simultaneously register with said casing ports, one of said valve ports being shaped so that it is fully opened before and 50 remains fully open when the other is open.

2. The combination of a multiple burner comprising independent burner tubes and burner tips, a gas delivery manifold having nozzles delivering to said burner tubes, said manifold being provided with a partition dividing it into chambers with a part of the nozzles opening into each, a gas supply valve comprising a casing having separate ports opening into said manifold chambers and a 55 gas supply connection at its rear end, and a rotary valve having a longitudinal passage communicating with said supply connection and ports adapted to simultaneously register with said casing ports, one of said valve ports being shaped so that it is fully opened 65

before and remains fully open when the other is open.

3. In a structure of the class described, the combination of a multiple burner having a plurality of independent burner members, a gas delivery manifold having a plurality of delivery nozzles coacting with said burner members, said manifold being provided with a plurality of chambers, a part of said nozzles communicating with each 75 chamber, a gas supply valve comprising a casing having separate ports communicating with said manifold chambers, and a rotary valve provided with ports adapted to be successively opened, one port being fully 80 opened prior to and remaining open when the other is opened.

4. The combination of a multiple burner comprising independent burner tubes and burner tips, a gas delivery manifold having nozzles delivering to said burner tubes, said manifold being provided with a longitudinally disposed zig-zag partition dividing it into chambers with alternate nozzles opening into each, and a gas supply valve, 85 having separate ports for admitting gas to said chambers, one of said ports being adapted to be fully opened before the other and to remain fully open when the second is opened.

5. The combination of a multiple burner comprising independent burner tubes and burner tips, a gas delivery manifold having nozzles delivering to said burner tubes, said manifold being provided with a partition 100 dividing it into chambers with a part of the nozzles opening into each, and a gas supply valve, having separate ports for admitting gas to said chambers, one of said ports being adapted to be fully opened before the other and to remain fully open when the second is opened.

6. In a structure of the class described, the combination of a plurality of radiating elements, a burner comprising a plurality of 110 independent burner members operatively associated with such radiating elements, said burner being provided with two gas chambers connected with alternating burner members, and a valve for controlling the delivery of gas to said gas chambers adapted to supply gas to one of them or to both, so that alternating radiating elements may be heated or all of them as desired.

7. In a structure of the class described, 120 the combination of a plurality of radiating elements, a multiple burner having a plurality of independent burner members operatively associated with said radiating elements, a gas delivery manifold having a 125 plurality of delivery nozzles coacting with said burner members, said manifold being provided with two chambers, a part of said nozzles communicating with each chamber, a gas supply valve comprising a casing hav- 130

ing separate ports communicating with said manifold chambers, and a valve provided with ports adapted to be successively opened, one port being fully opened prior to and

5 remaining open when the other is opened.

8. In a structure of the class described, the combination of a plurality of radiating elements, a multiple burner having a plurality of independent burner members oper-

10 atively associated with said radiating elements, a gas delivery manifold having a plurality of delivery nozzles coating with said burner members, said manifold being provided with two chambers, alternate noz-

15 zles communicating with each chamber, a gas supply valve comprising a casing having separate ports communicating with said manifold chambers, and a valve provided with ports adapted to be successively opened,

20 one port being fully opened prior to and remaining open when the other is opened.

9. In a structure of the class described, the combination of a plurality of radiating elements, a multiple burner having a plurality

25 of independent burner members each operatively associated with a radiating element, a gas delivery manifold having a plurality of delivery nozzles coating with said burner

members, said manifold being provided with a plurality of chambers, a part of said nozzles communicating with each chamber, and a gas supply valve controlling the admission of gas to said manifold chambers and adapted when in one position to cut off the gas from all the chambers, when in another position to admit gas to one chamber only, and when in still another position to admit gas to all the chambers.

10. In a structure of the class described, the combination of a plurality of radiating elements, a plurality of burner members operatively associated therewith and a single control valve for said burner members adapted to deliver gas to a portion or to all of the burner members whereby a part 40 of the radiating elements may be heated independently of the others or all of the radiating elements may be heated together.

In witness whereof I have hereunto set my hand and seal in the presence of two 50 witnesses.
